US0D1001120S

(12) **United States Design Patent** (10) **Patent No.:** **US D1,001,120 S**
(45) **Date of Patent:** **** Oct. 10, 2023**

(54) **TONEARM**

(71) Applicant: **Weizhou Tan**, Shaoguan (CN)

(72) Inventor: **Weizhou Tan**, Shaoguan (CN)

(73) Assignee: **Weizhou Tan**, Shaoguan (CN)

(**) Term: **15 Years**

(21) Appl. No.: **29/852,170**

(22) Filed: **Sep. 2, 2022**

(51) **LOC (14) Cl.** **14-01**

(52) **U.S. Cl.**

USPC **D14/262**

(58) **Field of Classification Search**

USPC D14/260, 260.1, 261–265, 299

CPC A63H 13/00; G11B 3/5836; G11B 3/31;

G11B 3/02; G11B 3/095; H04R 17/04;

H04R 23/00

(57) **CLAIM**

The ornamental design for a tonearm, as shown and described.

DESCRIPTION

FIG. 1 is a front perspective view of a tonearm, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the tonearm, which form no part of the claimed design.

1 Claim, 7 Drawing Sheets
